US0D1061170S

(12) **United States Design Patent** (10) **Patent No.:** **US D1,061,170 S**
(45) **Date of Patent:** **** Feb. 11, 2025**

(54) **VACUUM CONTAINER**

(71) Applicant: **Aktiebolaget Electrolux**, Stockholm (SE)

(72) Inventor: **Johan Hedberg**, Stockholm (SE)

(73) Assignee: **Aktiebolaget Electrolux**, Stockholm (SE)

(**) Term: **15 Years**

(21) Appl. No.: **29/821,538**

(22) Filed: **Dec. 30, 2021**

(30) **Foreign Application Priority Data**

Jul. 2, 2021 (EM) 001482483-0001

Jul. 2, 2021 (EM) 001482483-0002

(57) **CLAIM**

The ornamental design for a vacuum container as shown and described.

DESCRIPTION

FIG. 1 is a front perspective view of a first embodiment of a vacuum container showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a front perspective view of a second embodiment of a vacuum container showing my new design;

FIG. 8 is a front view thereof;

FIG. 9 is a rear view thereof;

FIG. 10 is a right side view thereof;

FIG. 11 is a left side view thereof; and,

FIG. 12 is a top view thereof.

The broken line showing of the dial and the base of the vacuum container form no part of the claimed design.

1 Claim, 12 Drawing Sheets
